UNITED STATES PATENT OFFICE

159,094

NURSING BRASSIÈRE

Edmée Pépin, Northampton, England

Application December 22, 1948, Serial No. 150,322
In Great Britain September 6, 1948

Term of patent 14 years

(Cl. D20—4)

To all whom it may concern:

Be it known that I, Edmée Pépin, of French nationality, residing at Northampton, England, have invented a new, original, and ornamental Design for a Nursing Brassière, of which the following is a specification, reference being had to the accompanying drawings, forming part thereof.

In the drawings

Fig. 1 is a front perspective view, and

Fig. 2 is a rear perspective view of a nursing brassière showing my new design.

I claim:

The ornamental design for a nursing brassière, as shown.

EDMÉE PÉPIN.
